US0D1067833S

(12) **United States Design Patent** (10) **Patent No.:** **US D1,067,833 S**
(45) **Date of Patent:** **** Mar. 25, 2025**

(54) **FOUR WHEELED ROLLATOR**

(71) Applicant: **Foshan Highway Medical Equipment Co. Ltd**, Foshan (CN)

(72) Inventor: **Liangyang Fang**, Foshan (CN)

(73) Assignee: **Foshan Highway Medical Equipment Co. Ltd**, Foshan (CN)

(**) Term: **15 Years**

(21) Appl. No.: **29/964,633**

(22) Filed: **Sep. 24, 2024**

(30) **Foreign Application Priority Data**

Jun. 5, 2024 (CN) 202430341695.4

(51) **LOC (15) Cl.** **12-12**

(52) **U.S. Cl.**

USPC **D12/130**; D12/131
